UNITED STATES PATENT OFFICE.

JOSEPH STREMEL, OF EVERETT, WASHINGTON, ASSIGNOR OF ONE-HALF TO NICHOLAS SCHOMMERS, OF SPOKANE, WASHINGTON.

OPERATING HEAD FOR OBSTRUCTION REMOVERS.

Application filed December 21, 1925. Serial No. 76,830.

My present invention relates to improvements in operating heads for obstruction removers especially adapted for use by plumbers and others in removing obstructions in sewerage and other pipes built in dwellings and other building structures. As is well known to those familiar with plumbing operations it is customary to remove obstructions from sewerage and other drain pipes by introducing a flexible tool of suitable length having a cutting head at its working end, and turning or twisting the tool at the operating end of the tool to cause the cutting head to ream or cut away the obstruction. After the removal of the obstruction the flexible tool is withdrawn and the pipe cleaned by passing water therethrough.

In such operations the débris carried by the flexible tool as it is withdrawn from the pipe is frequently scattered about the bathroom or other place where the tool is in use, causing discomfort, inconvenience and unsanitary conditions.

The primary object of my invention is the provision of means in the form of a manually operated head for the tool by means of which the flexible tool and its cutter may with facility be fed into the tortuous pipe for its work and then operated to remove the obstruction. As the flexible tool is withdrawn from its work means are provided for compactly stowing it away ready for subsequent use; and means are provided for gathering the débris carried by the tool as it is withdrawn to prevent scattering about in the room or other place where the work is being carried on.

The invention consists in certain novel combinations and arrangements of parts involving the use of a rotary head and a reel carried thereby, together with other features for operating and controlling the operation of the head and reel, as will hereinafter be more fully set forth and claimed.

In the accompanying drawings I have illustrated one complete example of the physical embodiment of my invention wherein the parts are combined and arranged in accordance with the best mode I have thus far devised for the practical application of the principles of my invention.

Figure 1 is a top plan view of the operating head embodying my invention.

Figure 2 is a view in side elevation of the device of Figure 1.

In carrying out my invention I utilize a supporting frame comprising a base plate 1 and posts 2 in which a drip pan 3 is supported, and the frame is of convenient size to render the device portable but at the same time provide an adequate support for the operating parts of my device. In use the operating head is placed upon a suitable support, or if more convenient it may be held in the hand and its operation controlled manually.

Between the posts a tool head 4 is supported, this head being in the form of a generally rectangular, open frame, normally disposed in horizontal position and capable of being revolved or rotated upon a pair of longitudinally disposed trunnions 5 and 6 at its ends. The trunnion 5 is hollow as shown while the trunnion 6 is a solid stud shaft, the former being journaled in a bearing 7 on one post and the latter journaled in a special bearing 8 on the other post. The bearing 8 is a split bearing and designed to perform the functions of a friction brake or clutch and is therefore provided with perforated ears 9 in which a clamp bolt 10 operates. By tightening the bolt the bearing 8 may be used as a clutch to prevent rotation of the trunnions in their journal-bearings. When the bolt is loosened the trunnions are free to turn in their bearings. For rotating or turning the rotary tool head a crank handle 11 is affixed on the solid trunnion 6 outside of the frame and the tool head 4 is controlled in its movement by manual power applied to the crank handle.

The rotary head is designed to twist or turn the flexible tool 12 which carries at its working end a cutter head and cutter (not shown) after the tool has been introduced into a pipe that is obstructed. The flexible tool is passed through the hollow trunnion 5 in line with the axis of the tool head 4 and a guide pulley 13, which is loose and laterally movable on an axle 14 supported transversely of the tool head and guides the flexible tool to a reel 15. The shaft 16 of the reel is journaled transversely of the rotary axis of the tool head or frame 4 in bearings 17 at opposite sides of the rotary head and the reel which is located within the open tool head 4 may be turned by the crank handle 18 located outside the rotary tool head.

The reel and its shaft together with the

flexible tool wound on the reel rotate bodily with the rotary head when it is turned by manipulating the crank handle 11. Thus it will be apparent that the handle 11 may be turned to advance the flexible tool with a screw action into the pipe to be cleaned, and the cutter head on the working end of the flexible tool cuts through the obstruction. Then by a reverse motion of the crank handle 11 the tool head and reel may be turned if necessary to release the flexible tool and cutter from entanglement in the pipe. To withdraw the tool from the pipe it may be wound upon the reel by turning the handle 18, and as the tool is withdrawn the débris therefrom will fall into the drip pan 3.

To retard the rotation of the reel, or to hold the reel and its shaft against rotation when the tool head is being rotated or revolved by manipulation of the crank handle 11, a friction brake or clutch is used in connection with the reel. This brake or clutch comprises a screw bar 19 having a friction head 20 for frictional engagement with one side face of the reel, and an operating head 19'. The screw bar is threaded into a bearing 21 of the tool head and it will be apparent that by turning the screw bar to cause frictional engagement of the head 20 with the side face of the reel the movement of the latter may be retarded or the reel may be held stationary with relation to the tool head.

The flexible tool 12 is usually a spiral

wound tube or closely coiled spring and as it is turned and twisted by the manipulation of the crank handle 11 to rotate the head 4 the tool enters the pipe and advances to the obstruction with a screw movement. The flexibility of the tool of course permits it to pass bends, joints, and other features in the pipe line and the interior surfaces of the pipe line confine the tool within the pipes for its work.

Having thus fully described my invention what I claim as new and desire to secure by Letters Patent is:—

An operating tool head, comprising the combination with a supporting frame having a pair of aligned bearings therein, one of said bearings being split, of a rotary tool head including an open frame having a hollow trunnion on one end thereof and a solid trunnion on the opposite end, means for clamping said split bearing on said solid trunnion to prevent rotation of said tool head, an operating handle on said solid trunnion for rotating said tool head in said bearings, a reel journalled in said open frame, operating means associated with said reel, means carried by said open frame and adjustable therein to retain the reel against rotary movement, and a flexible tool passing through said hollow trunnion and adapted to be wound on said reel.

In testimony whereof I affix my signature.

JOSEPH STREMEL.
